UNITED STATES PATENT OFFICE.

ALBERT A. PAULY, OF YOUNGSTOWN, OHIO.

CONCRETE CONSTRUCTION.

No. 829,228.

Specification of Letters Patent.

Patented Aug. 21, 1906.

Application filed February 28, 1906. Serial No. 303,145.

To all whom it may concern:

Be it known that I, ALBERT A. PAULY, a citizen of the United States of America, residing at Youngstown, in the county of Mahoning and State of Ohio, have invented certain new and useful Improvements in Concrete Construction, of which the following is a specification, reference being had therein to the accompanying drawings.

This invention relates to certain new and useful improvements in concrete construction; and the invention relates more particularly to the construction of retaining-walls, piers, abutments, foundations, and buildings from a plastic material, such as concrete.

The primary object of this invention is to provide a concrete construction wherein the use of facing-boards and retaining-frames are entirely dispensed with during the construction of a wall, building, or the like.

Another object of this invention is to provide a novel form of concrete block which can be assembled to form the facing or exterior finish of a wall. The formation of my improved blocks is adapted to firmly bind the concrete of a wall or like structure and retain the same in shape or form until it has become thoroughly seasoned or hardened.

The concrete blocks used in my improved construction, to be hereinafter described, are the subject-matter of applications for patent filed January 22, 1906, Serial Nos. 297,167 and 297,168, one of said applications being for an apparatus for forming artificial building-blocks from concrete while the other of said applications is a process for the manufacture of said blocks. In these applications I disclose an apparatus for manufacturing a flanged concrete block, and these blocks form the foundation of the present invention, which will be hereinafter more fully described.

Referring to the drawings accompanying this application, like numerals of reference designate corresponding parts throughout the several views, in which—

Figure 1 is a perspective view of a portion of a wall constructed in accordance with my invention, illustrating the arrangement of my improved concrete blocks and the manner in which they are tied together. Fig. 2 is a cross-sectional view of a portion of a wall constructed in accordance with my invention. Fig. 3 is a plan of the same, illustrating the construction of a corner or angle in the wall. Fig. 4 is a vertical sectional view of one of my

improved concrete blocks which can be used in connection with a wall or the like structure.

To put my invention into practice, I employ a plurality of concrete blocks 11 and 22, said blocks being identical in construction. Each block conforms to a channel-bar in shape, having its longitudinal edges provided with flanges 33. The blocks prior to their use in connection with a structure are thoroughly seasoned or hardened, as set forth in one of the above-mentioned applications, and are then assembled to confront one another, as clearly illustrated in Fig. 1 of the drawings. The flanges 33 of the blocks are adapted to extend inwardly and form a space which is filled with concrete or like plastic material 4.

In the construction of a wall the blocks 11 are arranged upon the upper edges of the blocks 22 and cement or the like adhesive material 5 is employed for securing the coinciding flanges 3 of the blocks 11 and 22 together. Prior to placing the blocks 11 upon the blocks 22 I use transverse wall-ties 6, said ties consisting of rods having T-shaped heads 7, which lie upon the flanges 3 of the blocks 11 and 22.

To retain the blocks 11 and 22 in position while the concrete or plastic material 4 is being placed between the blocks, I use straps or stirrups 7, which are placed over the blocks, to retain them in position and prevent them from spreading while the concrete or plastic material 4 is being tamped and thoroughly packed between the blocks 11 and 22. The ties 6 are embedded within the cement 5 and the concrete 4 and are adapted to serve functionally as tie-rods between the faces or concrete blocks of the wall being formed.

In constructing a wall one tier or row of two-high blocks is arranged together with the ties 6 and held together by straps or stirrups 7 while they are being filled and tamped with concrete. The concrete between the blocks is then permitted to settle and season before the straps or stirrups 7 are removed. After one tier of two-high blocks has been so constructed another similar tier may be constructed upon the first tier until the wall has been entirely built. In this connection I do not care to confine myself to a two-high-block tier, as another row of blocks may be arranged upon those shown and retained together by a strap or stirrup having longer depending arms.

In constructing an angle in a wall or the corner of a structure a concrete block 8 is arranged at the ends of the longitudinally-disposed blocks 1 1 while the blocks 9 9, forming the angle, are arranged to abut against one of the blocks 1. A tie 10 of a greater length than the tie 6 is arranged at an angle to the blocks 1 to partially lie upon the top edges of the blocks 9 9 and the blocks 1 1, thereby binding the blocks 9 9 to the blocks 1 1 when a wall has been built.

In Fig. 4 of the drawings I have illustrated a concrete block 11, such as disclosed in the above-mentioned applications, and this block 15 may be readily used in lieu of the blocks 1 1 and 2 2, the only difference residing in the end flanges 12 of the block being retained, and these flanges when confronting another similar block may be secured together by cement or the like adhesive material. (Not shown.) My invention particularly resides in forming a wall or the like structure of channel-shaped concrete blocks, which form a facing for the wall and dispenses with retaining boards or frames being employed 25 while the wall is being constructed. By this means I reduce the cost of constructing a

wall or like structure and dispense with a lot of labor and superfluous material heretofore necessary in constructing a wall. It is obvious that my improved concrete blocks may be constructed of various sizes and arranged to form walls or the like structures of considerable size, and such changes as are permissible by the appended claim may be resorted to without departing from the spirit and scope of the invention.

What I claim, and desire to secure by Letters Patent, is—

A composite wall composed of composite building-blocks of channel-bar form disposed in two parallel rows, each row of blocks being two blocks high and cemented together, tie-rods having their ends embedded in the cement between the blocks of each row and connecting the rows together, and a solid filling of concrete between the rows of composite blocks.

In testimony whereof I affix my signature in the presence of two witnesses.

ALBERT A. PAULY.
